(57) **CLAIM**

The ornamental design for a fender extension, as shown and described.

DESCRIPTION

FIG. 1 is a perspective view of a fender extension, showing an embodiment of our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a perspective view of a fender extension, showing another embodiment of our new design, which is a mirror image of the fender extension shown in FIGS. 1-6.

FIG. 8 is a front elevational view thereof.

FIG. 9 is a rear elevational view thereof.

FIG. 10 is a right side elevational view thereof.

FIG. 11 is a left side elevational view thereof; and,

FIG. 12 is a top plan view thereof.

Stippling in the drawings represent the three-dimensional contours of the design, and is not intended to indicate surface decoration. The broken lines shown in the drawings depict portions of the fender extension that form no part of the claimed design.
